J. M. CAMPANA.
WINDOW.
APPLICATION FILED MAR. 29, 1911.

1,073,956.

Patented Sept. 23, 1913.

UNITED STATES PATENT OFFICE.

JOHN M. CAMPANA, OF MORRISTOWN, NEW JERSEY.

WINDOW.

1,073,956.

Specification of Letters Patent. Patented Sept. 23, 1913.

Application filed March 29, 1911. Serial No. 617,585.

To all whom it may concern:

Be it known that I, JOHN M. CAMPANA, a citizen of the United States, residing at Morristown, in the county of Morris and 5 State of New Jersey, have invented certain new and useful Improvements in Windows; and I do hereby declare the following to be a full, clear, and exact description of the invention, such as will enable others skilled 10 in the art to which it appertains to make and use the same.

My invention relates to windows, but has reference more particularly to new and useful improvements in sash-frames and to 15 means for permitting the ready removal thereof when occasion requires.

It has among other objects that of greatly facilitating the dangerous operation of window cleaning, painting or reglazing, and 20 consequently safeguarding the lives and limbs of persons thus employed.

For a further object it contemplates the production of a simple, light and inexpensive attachment for one side-rail of a window frame whereby the latter may be rendered laterally expansible and contractible 25 for the purpose either of securely retaining it in its coöperating window casing, or instantly releasing it therefrom, as may be desired.

The invention also contemplates and provides for certain novel structural features which are designed and adapted to produce the results aforesaid.

35 The invention will be hereinafter particularly described and pointed out in the claims following.

In the accompanying drawings which 40 form part of this application, and whereon corresponding numerals refer to like parts in the several views: Figure 1 is a side elevation of a window frame or casing, having upper and lower sashes the latter equipped with my invention. Fig. 2 is a horizontal 45 section of the invention in its relation to a window casing, taken on the line 2—2, Fig. 1. Fig. 3 is a perspective view of the invention projected from the side-rail of a sash frame, and of one securing bolt also projected at right angles, both leading features 50 of this figure being broken away for convenience of arrangement upon the sheet. Fig. 4 is an interior perspective view of a modified form of attachment also broken 55 away for economy of space.

Reference being had to the drawings

and numerals thereon, 5 indicates a window frame or casing, and 6 the window sill of any well known construction and provided with the usual vertical partition or guide 60 strips 7, as best shown by Fig. 2. Within the casing 5 and upon opposite sides of strips 7 are located vertically movable upper or outer and lower or inner window sashes 8 and 9, respectively, both counterbalanced by weights 10 and sash-cords 11 passing over sheaves (not shown) in the upper opposite sides of the window frame or casing 5.

To one side-rail of the sash frame 9, 70 preferably the left as shown, is attached a metallic casing 12 of relatively stiff spring metal, shaped by dies to cross the vertical edge of said rail and to extend in parallel lines across the front and back thereof. This 75 casing is broken at both sides by oppositely and horizontally arranged attaching slots 13, 13, and through the latter project the opposite ends of securing bolts 14, 14 by which the casing is bound to the sash and 80 secured in laterally adjusted positions. Preferably, but not necessarily, the side-rail of frame 9 may be reinforced by a thimble or tubular bearing 15 driven into berings 16, and the bolts 14 may be provided with wing-nuts 17, but obviously the said bearings may be omitted, and for said wing-nuts may be substituted various other forms of nuts either flush or projected as convenience and circumstances may suggest. When, however, the tubular bearings 15 or their equivalents are employed these elements should be of a length not exceeding the width of the side-rail through which they pass in order 90 not to interfere with the spring of the side 95 walls of the casing 12 and its consequent binding action. It will be noted moreover, that the inner edge of the casing 12 is configured by one or more raised thumb or finger holds 18 to facilitate moving the casing into its adjusted position, and while for convenience shown at the edge as stated, these projections 18 would obviously perform their intended functions equally well at any other point or points upon the 100 surface of the casing. At the upper end of casing 12 as best shown by Fig. 3, is provided a vertical slot 19 the object whereof is to permit passage of the customary sash-weight cord from the frame 9 to the counterbalancing weights 10 in the window frame.

In the modified form of attachment illus-

trated by Fig. 4, intended more especially for sashes of unusual length, an additional central set of attaching slots may be employed and both top and bottom ends of the metallic casing are shown substantially closed.

This being a description of my invention it will be quite obvious that the removal of the window sash 9, or both sashes 8 and 9 10 provided both are equipped with my invention, may be instantly accomplished without difficulty, the window cleaned or repaired by an operative within the building, and as quickly returned without the 15 slightest risk of life or limb. In this operation nuts 17, 17 are released, metallic casing withdrawn from its vertical slide or 20 guide-way by agency of its thumb holds 18, and the window-sash swung upon its sash-cords into the room. In replacing the 25 frame the aforesaid operation is simply reversed, the frame being laterally expanded by projecting the casing 12 into its vertical guide-way and there retained by action of bolts 14 and nut 17 or the equivalent.

Having thus described my invention, what I claim and desire to secure by Letters Patent is:

1. A window frame and sash therefor in 30 combination with a laterally adjustable casing having flexible sides which embrace one side rail of the sash frame, and means extending through the sash frame by which the sides of the casing may be drawn toward 35 each other into engagement with the sash frame to lock the casing in a projected operative position for retaining the sash within both runways of the window frame, the width of the sash being such that said sash 40 and the casing may be removed bodily from the runways of the window frame.

2. A window frame and sash therefor in 45 combination with a laterally adjustable casing having flexible sides which embrace one side rail of the sash frame and are freely movable in both directions with relation

thereto, and bolts extending through the sash frame by which the sides of the casing may be drawn toward each other into engagement with the sash frame to lock the casing in a projected operative position for retaining the sash within both runways of the window frame, the width of the sash being such that said sash and the casing may be removed bodily from the runways of the window frame. 50 55

3. A window frame and sash therefor in combination with a laterally adjustable casing U-shaped in cross section having flexible sides which embrace the side rail of the sash frame, and means extending through the sash frame by which the sides of the casing may be drawn toward each other into engagement with the sash frame to lock the casing in a projected operative position for 60 retaining the sash within both runways of the window frame, the width of the sash being such that said sash and the casing may be removed bodily from the runways of the window frame. 65 70

4. In a window frame and sash therefor in combination with a laterally adjustable casing having flexible sides which embrace one side rail of the sash frame and are perforated by oppositely disposed elongated slots, 75 and bolts extending through the sash frame as also through each pair of said slots by which the sides of the casing may be drawn toward each other into engagement with the sash frame to lock the casing in a projected operative position for retaining the sash within both runways of the window frame, the width of the sash being such that said sash and the casing may be removed bodily from the runways of the window frame. 80 85

In testimony whereof I affix my signature, in presence of two subscribing witnesses.

JOHN M. CAMPANA.
